CUP HOLDER

John A. Kappeler, Dayton, Ohio, assignor of one-half to
Gertrude C. Kappeler, Dayton, Ohio

Application October 29, 1953, Serial No. 389,041

9 Claims. (Cl. 248—1)

This invention relates to cup holders, and particularly to devices for temporarily gripping and holding relatively soft and deformable cups such as cylindrical paperboard containers of a kind commonly used in the "carry-out" of foods and beverages.

According to one aspect thereof, the instant invention contemplates a new use for containers of the class described whereby they may serve as disposable outdoor floral vases, for example in grave decoration. Thus, it is proposed that the cup holder of the present invention shall be constructed and arranged for permanent installation in the ground and shall provide means for temporarily receiving and gripping paperboard containers.

The object of the invention is to simplify the construction as well as the means and mode of use of cup holders, whereby such holders may not only be economically manufactured, but will be more efficient in use, of relatively long life, easily adaptable to different cups, while having relatively few parts and be unlikely to get out of repair.

A further object of the invention is to provide a cup holder of the kind described in which the cup or container can easily be mounted and as easily removed.

Another object of the invention is to provide interlocking means between the holder and cup resisting accidental withdrawal or dislodgment of the cup from the holder, as by windstorm.

A further object of the invention is to achieve the above mentioned interlocking connection without especially constructed containers, it being an accessory object in this connection to permit the use of any of the standard forms of paperboard container in the present cup holder.

A still further object of the invention is to make the cup holder of relatively inexpensive material, such as sheet metal, which can be readily stamped and formed and which is not subject to early deterioration from wear and the weather.

A further object of the invention is to provide a cup holder possessing the advantageous structural features, the inherent meritorious characteristics and the mode of use herein mentioned.

With the above primary and other incidental objects in view as will more fully appear in the specification, the invention intended to be protected by Letters Patent consists of the features of construction, the parts and combinations thereof, and the mode of operation, as hereinafter described or illustrated in the accompanying drawings, or their equivalents.

Referring to the accompanying drawing, wherein is found one, but obviously not necessarily the only, form of embodiment of the invention,

Fig. 1 is a view in side elevation, partly broken away, of a cup holder in accordance with the illustrated embodiment of the invention, a fragment of a cup being shown mounted therein;

Fig. 2 is a view in plan of a spider member comprised in the cup holder, after stamping but before forming;

2

Fig. 3 is a view in plan of the member of Fig. 2, after forming; and

Fig. 4 is a view in side elevation of the member of Fig. 3.

5 Like parts are indicated by similar characters throughout the several views.

Referring to the drawings, a cup holder in accordance with the illustrated embodiment of the invention is constructed and arranged for installation in the ground. It comprises a cylindrical receptacle 10, open at one end and closed at the other end except for drain openings 11. At the open end thereof, the receptacle 10 is provided with a peripheral flange 12. Thus, the receptacle 10 may be disposed within a hole in the ground, the flange 12 limiting against the ground surface in a manner to maintain the open or upper end of the receptacle substantially in the plane of such surface.

Dependent from the bottom of the receptacle 10 is an externally projecting, irregularly shaped member 14. The member 14 serves as an anchor, it being proposed that the holder be supported in spaced relation with a concrete footer, with the member 14 embedded therein.

A spider or supporting member 15 is mounted in the receptacle 10. It is made up of a disc-like body portion 16 disposed in a plane normal to the longitudinal axis of the receptacle, or in a manner to lie transversely across the interior of the receptacle near the open end thereof. The body portion 16 is concentric in the receptacle and is spaced from the wall thereof. Further comprised in the spider 15, and formed integrally with the portion 16 is a circumferential series of circularly spaced, depending tongues 17. The extremities of the tongues 17 are expanded in a radial sense in order that they may contact the wall of the receptacle, to which they are secured by spot welding, riveting or the like.

In alternating relation to the tongues 17, and also formed integrally with the body portion 16, is a series of tongues 18, there being spaces 19 formed between the adjacent tongues 17 and 18. The tongues 18 are circumferentially aligned with the base portions of the tongues 17, but are shorter than the tongues 17, terminating above the expanded portions thereof. On the tip of each tongue 18 is an inclined wedge formation projecting peripherally thereof, the several such formations complementing one another to define a discontinuous screw thread 21.

The tongues 18 and the base portions of the tongues 17 define, with the wall of the receptacle 10, a slot 22 which opens through the open upper end of the receptacle.

A fragment of the cup to be held is shown in Fig. 1, where it is shown to be a known kind of paperboard container 23 having a closed bottom wall 24 and a downwardly projecting peripheral flange wall 25. In mounting the cup 23 in the present cup holder, it is aligned therewith and the flange wall 25 is inserted into the slot 22, being pressed in place by an axial thrusting movement until the flange wall embraces at least a part of the screw-like or wedge projections 21. The cup 23 is then rotated, 55 relatively to the receptacle 10 and member 15. As a result of such motion the screw-like projections 21 form corresponding screw threads in the relatively soft material of the flange wall 25, interfitting with these screw threads and applying a reactant force to the cup 23 tending to draw it downward toward a seat on the body portion 16. The cup 23 is in this manner interlockingly engaged with the spider member 15, and is held securely thereby in an erect position. The cup is detachable from the cup holder merely by applying rotative and axial forces which 60 are the reverse of those used in mounting the cup.

The receptacle 10 and spider member 15 may be made of any suitable materials and by any convenient method.

The receptacle 10, for example, may be drawn sheet metal. The member 15 may be a metal stamping, constructed in a first or stamping step to produce a semi-finished article as shown in Fig. 2, followed by one or more forming steps producing the finished article as shown in Figs. 3 and 4.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features, shown, but that the means and construction herein disclosed comprise but one of several modes of putting the invention into effect.

Having thus described my invention, I claim:

1. A cup holder, including a receptacle open at one end and substantially closed at the other, and spider means installed in said receptacle intermediate the ends thereof, said spider means including a disc concentric with said receptacle and received therein with clearance between its outer edge and the wall of the receptacle, tongue element on said disc depending from the peripheral edge thereof toward the closed end of the receptacle and expanded radially at their lower extremities for cooperative engagement with the wall of the receptacle, and a plurality of other tongues similarly depending from the peripheral edge of said disc toward the closed end of the receptacle and spaced circularly from said tongue element, said other tongues being formed with cup engaging means integral therewith and arranged to anchor a cup in said receptacle on seating thereof to said disc.

2. A cup holder, including an open ended receptacle, a cup supporting member concentrically mounted in said receptacle and having a body portion lying in a plane normal to the axis of the receptacle and further having a depending portion, said depending portion defining with the internal wall of said receptacle an annular slot for receiving the base edge of a service cup of paper or the like, and screw-like means on said depending portion for engaging the base edge of the service cup on rotative insertion thereof in the annular slot.

3. A cup holder, including a receptacle open at one end thereof, a cup supporting member concentrically mounted in said receptacle in inverted position and having a body portion lying in a plane normal to the axis of the receptacle and further having a depending circumferential series of integral tongues, at least a portion of said tongues being off-set and in engagement with the wall of the receptacle for mounting of said supporting member in said receptacle, and at least one other of said tongues being formed with screw-like portions.

4. A cup holder, including a receptacle open at one end and adapted to be seated in a hole in the ground, said receptacle having at said one end an outwardly projecting flange engageable with the ground surface as it seats therein, an external projection on the other end of said receptacle for anchoring of the receptacle in the ground, a spider supported in said receptacle and for seating a cup inserted in said one end of the receptacle, and means on said spider for effecting an interlocking

engagement with the cup for peripherally and releasably engaging of the cup in said receptacle as it is rotatively seated therein.

5. A holder for the releasable gripping and maintaining in an erect position of a cup made of a deformable material, including a receptacle for receiving the bottom of a cup through one end thereof, a spider installed in said receptacle intermediate the ends thereof, and means on said spider for effecting a detachable interlocking engagement of the cup on rotative application of the cup thereto.

6. A holder according to claim 5, characterized in that said last named means comprises screw threads on said spider means forming and interfitting with corresponding threads on said cup in response to relative rotation of said cup and spider means in one direction.

7. A cup holder for a cup having a depending circumferential base edge comprising, a receptacle open at one end thereof, a spider mounted in said receptacle and having circularly spaced means depending therefrom and engaging said receptacle to define therewith a circular recess for receiving the depending circumferential base edge of a cup as it seats to said spider, a portion of said circularly spaced means having peripheral projections of

25 a wedge shaped nature projecting within said cup receiving recess whereby on rotation of the cup relative said receptacle as it is inserted to have its depending edge seat in said recess, said peripheral projections will anchor to the cup and prevent dislodgement thereof.

30 8. A cup holder for a cup having a depending circumferential base edge including a receptacle open at one end and substantially closed at the other, an inverted cup-like element mounted to said receptacle in the open end thereof, said element including a portion of lesser 35 diameter than said receptacle to define an annular slot therewith thereby for receiving a depending circular base edge of a cup as it is seated to said receptacle, and means on the said cup-like element projecting in said slot for engaging in the base edge of the cup on effecting a screw-like motion thereto on seating it in said receptacle.

9. A cup holder for a deformable service cup including, an open ended receptacle, a cup supporting member concentrically mounted in said receptacle having a radially expanded portion engaged to the inner wall thereof providing an annular recess adjacent the inner wall of said receptacle to receive the depending base edge of a deformable service cup therein, and anchoring means on said supporting member projecting within said annular recess in circularly spaced fashion for anchoring to the service cup on rotative seating thereof to said cup supporting member.
